MOLDER'S FLASK

Angelo B. Castagnola, Oakland, Calif.

Application March 27, 1946, Serial No. 657,594

2 Claims. (Cl. 22—107)

1

This invention relates to molders' flasks, and particularly to improvements in the kind of molders' flasks generally referred to as snap flasks because they include means to enable them to open quickly or to snap to an open position when it is desired to remove their contents.

The conventional molder's flask is of rectangular shape and its side walls are separable at at least two corners to enable them to be released from the sand mold form within it. In snap flasks springs are generally employed at the corners of separation to effect opening of the flask and clamp means are employed for opposing spring action and for holding the flask in closed position. The clamps and spring mechanisms usually project diagonally from the flask corners so that they prohibit resting the flask on one of its sides as it is being turned over or otherwise handled in use. The term flask as used herein refers to either of the parts of a flask, which comprises both cope and drag, since both parts are similar in construction and embody the same means for facilitating quick opening.

My invention provides a flask with quick opening means arranged to leave two opposite faces of the flask entirely clear of any obstructions or projections so that the flask can be rested on a support and one end forced against an abutment, the other end raised and the flask rolled over for removing the flask from the mold—inverting the cope and drag to place the component parts of the mold in their upright pouring position—without any danger of releasing the opening means during this inverting operation, or without requiring any careful handling by rolling the flask over on one corner, instead of broadly throughout the length of the face of the flask as is proper and safe with my invention.

The objects and advantages of the invention are as follows:

First, to provide a flask with quick opening means which leaves two sides of the flask free of all obstructions and projections so that the flask may be turned over as readily as a plain flask.

Second, to provide a quick opening means for molders' flasks which is simple in construction and quickly and easily operated.

Third, to provide a quick opening means for flasks which is easily adjustable and which will maintain its adjustment.

Fourth, to provide a quick opening means for the diagonally related corners of a flask and which is completely confined, including the operating members, to two sides of the flask whether

2

in closed or open position, whereby the other two sides of the flask are unobstructed and free of projections for easy turning of the flask.

Fifth, to provide a quick opening means as outlined which cannot be accidentally released when the flask is turned over.

Sixth, to provide a quick opening means as outlined which is quickly and easily adjusted at will and in which parts subject to wear are easily and quickly replaceable.

In describing the invention reference will be made to the accompanying drawings, in which:

Fig. 1 is a top plan view of a flask embodying the invention.

15 Fig. 2 is a front elevation of Fig. 1.

Fig. 3 is a fragmentary side elevation of Fig. 2 and partly shown in section.

Fig. 4 is a face view of the actuating member.

Fig. 5 is a face view of the actuating cam.

20 Fig. 6 is a diagrammatic plan view of a flask drawn to a reduced scale showing the clearance afforded by the invention, for rapid and easy turning of the flask.

The invention consists of a special corner structure for each of two opposite corners 10 and 11 of a flask 12 in which one side wall 13 has a diagonal outward and rearward projection 14 with the inner face 15 of the one side extending in line to a point 16 intermediate the width of the adjacent side wall 17 and thence projecting diagonally parallel with the diagonal edge 14 and terminating in a clamp face 18 angularly related to the sides 15 and 17. The terminal end of the adjacent side wall conforms 30 to the diagonal projection and includes a projection flange member 19 the outer end of which aligns with the side 14 of the diagonal projection.

40 A clamp boss 20 is formed on the forward end of the diagonal projection and a pair of pilot bosses 21 are located respectively above and below the boss 20 as shown. Clamp and pilot bosses 22 and 23 are formed on the flange member 19 in axial alignment with the bosses 20 and 21.

45 Threadedly secured in each pilot boss 23 is a pilot which has a threaded portion 24 extending from an enlarged portion 25 providing a shoulder or seat 26 for positive alignment of the pilot. The pilot 25 slidably operates in a bore 27 in the boss 21 and is backed up by a compression spring 28 which, through the pilot, urges opening of the flask to the degree indicated in Figs. 1 and 3, and thereby forms an essential part of the quick opening means.

50 55 The clamping means for closing the flask and

releasing the corners to open consists of a shaft or pivot indicated as a stud which has one end 28 threadedly secured in the boss 20 and is slideable in a bore 30 formed in the boss 22.

Seated on top of the boss 22 is a cam member 31 having an anchoring means such as a yoke 32 extending from one side to cooperate with an anchoring device such as a rib 33. The cam member has an axial bore 34 for the stud 35 constituting the pivot member. This cam member has cam surfaces 36 and 37 diametrically related in the top face.

Rotatably supported on the pivot member is a flask closing element 38 provided with an operating handle 39, and having a pair of sector teeth 40 and 41 projecting from the inner face to cooperate with the cam surfaces 36 and 37 and with a substantially flat face 42 at the top of the rise to provide a holding area. A nut 43 is adjustable on the pivot member 35 for suitable adjustment of the cam action, and suitable means is provided for securing the nut in adjusted position, such as a washer 44 having an inwardly projecting key 45 to fit the keyway 46 so that operation of the lever 39 will not act to loosen the nut or change its adjustment.

The pilots 25 keep the two sections of the flask in perfect alignment, and the springs 27 acting on the ends of the pilots urge the flask to open while the nut 43 limits opening to the extent indicated at 47, just sufficient to free the mold. When the flask is open, the teeth 41 are located at the bottom 48 of the cam surfaces with the springs maintaining that position, when the levers 39 are in one position.

For making the mold, the levers are moved to their other position which through the teeth 40 and 41 in cooperation with the cam surfaces 36 and 37 force the edges 15 and 17 of the flask together, closing the gap 47, with the teeth riding finally on the almost flat surface 42 where there will be no tendency for the members 40 and 41 to ride back down the inclined cam surfaces, thus effectively holding the flask closed.

The quick opening means including its operating lever is completely confined to one side of the flask, at no time ever projecting beyond the plane 49 of the other side 13, so that the adjacent sides 13 are entirely unobstructed, whereby the lower edge of either side 13 can be abutted against any suitable abutment 50. The back edge 51 can then be raised and the flask turned over without the necessity of guarding against accidental release of the flask corners.

To release the mold it is merely necessary to flip the handle 39 sufficient to move the cam teeth off of the high level spot, and the springs 27 will force the flask open to the extent as defined by the adjustment of the nut, as indicated at 47.

In case of wear, the cam can be quickly replaced by removing the nut, washer and handle, and merely slipping the old cam off and replacing it with a new one since no securing means is necessary, the rib or other suitable stop being all that is required. The handle with its cam teeth are likewise replaceable. In case of wear of the teeth or cam surfaces so that the flask does not close tight, a slight adjustment of the nut 43 is all that is necessary, the nut having a relatively tight fit on the screw thread to prevent its getting out of adjustment through vibration or jars.

It will be noted, as indicated in Fig. 6, that one of these quick-release clamp units is provided for each of two diagonally related corners

of each section of the flask, and that they are completely confined to respectively opposite sides of the flask leaving the other two sides entirely free of projections or obstructions of any kind, and with the other two sides functioning as guards for the clamp units so that they cannot be accidentally released when the respective sections, such as cope and drag are turned over.

The action is rapid and almost effortless; just a slight movement of the lever 39 causes the clamp to snap off while the springs acting on the pilots force the flask corners to spread.

The collar 26 limits the closing of the flask to maintain predetermined clearance so that foreign bodies entering or within the space 47 cannot prevent proper closing. This collar also functions as a gauge for adjustment of the clamping means.

The cam for the clamping means has continuing surfaces of different inclinations, the closing portion 48 having a sharp rise thence continuing at 42 into a rather flat rise and in turn terminating in the flat surface 52 between the cam surfaces.

The almost flat portion 42 has just enough inclination to compensate for slight wear on the clamping elements and yet not enough to cause the cam member 38 to ride back down the incline, being considerably less than the angle of friction between the surface 42 and the tooth 41. It therefore assures tight closing of the flask irrespective of a predetermined amount of wear on the various thrust surfaces.

I claim:

35 1. A molder's flask or the like comprising a rectangular frame made of two parts separable at diagonally opposed corners of the rectangle, resilient means urging separation of said parts, and clamping means operable to oppose the resilient means to bring said parts into closed relationship, said resilient means and clamping means being disposed outside the rectangular frame but entirely between the planes defined by two opposite sides of the rectangular frame whereby the frame may be supported on either of said sides on a plane surface.

40 2. A molder's flask or the like comprising a rectangular frame made of two parts separable at diagonally opposed corners, each of said corners comprising opposed plane surfaces parallel to the plane of one side of the rectangle and opposed plane surfaces parallel to the direction of separating movement and contiguous with the first plane surfaces and diagonally related to the first plane surfaces.

ANGELO B. CASTAGNOLA.
